United States Patent Office.

JOHN C. CLIME, OF PHILADELPHIA, PENNSYLVANIA.

Letters Patent No. 88,449, dated March 30, 1869.

IMPROVEMENT IN UMBRELLA-COVERS.

The Schedule referred to in these Letters Patent and making part of the same.

To all whom it may concern:

Be it known that I, JOHN C. CLIME, of Philadelphia, Pennsylvania, have invented a new and useful Umbrella-Cover; and I do hereby declare that the following is a full and exact description of the same, reference being had to the annexed drawings, forming part hereof, and to the several letters marked thereon, in which drawings—

Figure 1 represents a longitudinal section of an umbrella, with my cover applied thereto.

Figure 2, a similar section of the upper portion of the same, enlarged.

Figure 3, a similar section of the lower portion of the umbrella-stick, or staff, and of certain devices (enlarged) used in connection with the cover.

The body of my umbrella-cover is composed of a tube, or bag, of any woven or felted fabric or leather, gum cloth or other flexible material, provided at one (the upper) end with properly-formed devices for securing that end, and used in connection with certain other devices placed on the umbrella-stick, as herein-after described, the whole forming a cover, which completely envelops the folding-parts of the umbrella, and makes the latter a more convenient object in the hands of travellers.

In the drawings—

a represents the umbrella-stick, or staff.

b, the ribs.

c, the cloth fastened on the ribs.

d, the body of the cover, which is provided at its upper end with the devices *e* and *f*, and connects at its lower end, when in use, with the devices *g* and *h*, which work on the stick, and are not removed with the cover.

i is a cup-like device, which screws up and down on

the device *g*, and is intended to embrace the ends of the ribs *b* when the umbrella is closed.

The device *h* also screws up and down on the device *g*, and the lower end of the cover being closed by the drawing-strings *j*, below the flange *k*, on the device *g*, the device *h* is screwed up against said flange, and the cover thus secured.

The stick *a* is shown to be in two parts, each screwed into the device *g*. The upper part of the stick may, however, be without the screw-thread, and may be fastened to the device *g* with cement, or by having a rivet passed through both; and the mode of attaching the lower part, *a'*, of the stick to the device *g*, may be similarly varied.

The upper end of the body of the cover *d* is permanently fastened between the devices *e* and *f*, by screwing down the device *f* until the end of the body of the cover is compressed between the lower end of said device *f* and flange on device *e*, as shown in the drawings. The devices *e* and *f* go with the cover when it is removed.

The several devices may be made of metal, bone, ivory, vulcanite, or such other substantial material as may be desired, and they may be corrugated or otherwise exteriorly ornamented.

Having thus described my invention,

I claim, and desire to secure by Letters Patent—

The body *d*, of flexible material, and the devices *e* and *f*, combined and arranged with the flanged device *g*, and the devices *h* and *i*, substantially as and for the purpose set forth.

JOHN C. CLIME.
